UNITED STATES PATENT OFFICE.

ROBINSON BURT, OF BUFFALO, NEW YORK, ASSIGNOR TO F. N. BURT COMPANY, LIMITED, OF BUFFALO, NEW YORK, A CORPORATION OF ONTARIO, CANADA.

SLITTING-MACHINE.

1,286,934.

Specification of Letters Patent. Patented Dec. 10, 1918.

Original application filed July 10, 1913, Serial No. 778,255. (Patent No. 1,180,005, dated April 18, 1916.) Divided and this application filed March 7, 1916. Serial No. 82,527.

To all whom it may concern:

Be it known that I, ROBINSON BURT, a citizen of the United States, residing at Buffalo, in the county of Erie and State of

5 New York, have invented certain new and useful Improvements in Slitting-Machines, of which the following is a full, clear, and exact description, such as will enable others skilled in the art to which it appertains to

10 make and use the same.

This invention relates to slitting machines, and with respect to its more specific features, to machines of the character referred to for slitting paper boxes.

15 One of the objects of the invention is the provision of a practical device wherewith boxes, such as the small, relatively stiff paper boxes ordinarily employed as a container for cigarettes, may be slit on predetermined lines.

20 Another object of the invention is the provision of a simple and efficient machine wherewith the covering labels or paper strips on sectional paper boxes may be slit in line with the joint between the base and cover at one side of the box, thus permitting the label or strip to serve as a hinge between the base and cover at the opposite side of the box.

25 Another object of the invention is the provision of a practical machine of the character referred to wherein the combined slitting of the boxes, supplying boxes to be slit, and the removal of slitted boxes is entirely

30 automatic.

Other objects will be in part obvious and in part pointed out hereinafter.

The invention accordingly consists in the features of construction, combinations of 35 elements and arrangement of parts which will be exemplified in the construction hereinafter set forth, and the scope of the application of which will be indicated in the following claims.

40 In the accompanying drawings forming part of this specification, and wherein similar reference characters refer to similar parts throughout the several views,—

Figure 1 is a plan view of one embodiment 45 of the invention;

Fig. 2 is a sectional elevation on the line *x—x* of Fig. 1;

Fig. 3 is a rear end elevation of a portion of Fig. 1, enlarged;

Fig. 4 is a vertical section on line *y—y*, 55 Fig. 3;

Fig. 5 is a horizontal section through a portion of the mechanism on line *z—z*, Fig. 2;

Fig. 6 is a detail of the machine; 60

Fig. 7 is a transverse section of the box through the hinge; and

Fig. 8 is a perspective view of the labeled box, in open condition, after slitting.

The utility of this invention is prominently displayed when employed to slit the paper strip which is disposed around a two-part paper box, such as the small paper box ordinarily employed as a container for cigarettes. Such a box comprises a base 1 and 65

a cover 2, the base comprising a flange 3 and a collar or neck 4, and the cover comprising a flange 5. The flange of the cover slides over the neck 4, and the edge of the cover flange lies closely adjacent the shoulder of the base at the edge of the base flange.

Across the line of juncture 6 between the cover flange and the base flange is a strip of paper or other flexible material 7, usually 70

a label, and this strip may cover one face 80 of the box and extend across the said line of juncture or joint, at opposite sides of the box. This strip may be adhesively attached to the box on the face and sides during the manufacture of the box, and to open the box 85

is slit at one side opposite the joint, as at 8, the unsevered strip at the opposite side providing a hinge 9 between the cover and the base.

A machine for automatically applying a 90 label strip to a base and cover in the manner above described is disclosed in applicant's application filed July 10, 1913, Serial No.

778,255, patented April 18, 1916, No. 1,180,005, of which this application is a 95 division. As the present application has

more particularly to do with that part of the prior application relating to the slitting of the labeled boxes, the description herein 100 is confined to the mechanisms more particu-

larly concerned with the results sought herein, reference being made to the fuller disclosure of said prior application where necessary or desirable. The numeral 9' indicates a table or stationary frame, on which is supported a main driving shaft 10 having a belt pulley 11 loosely journaled thereon and provided with one element 12 of a friction clutch. A coöperative clutch element 13 is splined on the main driving shaft so as to be rotated thereby but having longitudinal movement thereon. The element 13 carries a grooved collar 14, the groove of which may be engaged by the fork of the usual shift rod. On the driving shaft 10 is a gear 15 meshing with a gear 16 on a counter shaft 17, supported in bearings 18; and a chain 19 communicates motion to a cam shaft 20 by means of bevel gears 21 and 22.

20 The boxes, labeled as hereinbefore described so that one or more of their faces, or portions thereof, include the labels, assume position opposite a box magazine, the boxes being supported in a pocket 23 in rotary carrier 24, having a discharging plunger 25, this carrier being the lower carrier of the apparatus disclosed in the prior application hereinbefore mentioned.

In rear, on a level with the position assumed by the labeled boxes when in position to be ejected from the lower carrier, is the box magazine just mentioned, into which the labeled boxes are successively pushed by the discharger 25 of the carrier, each succeeding box advancing the one ahead of it. This magazine comprises upright side walls 26 and 27 spaced apart sufficiently to permit the boxes to pass therebetween, and one of said walls, as 26, is free 40 to move toward and from the other sufficiently to press the label on the box where disposed across the joint between the cover and the base of the box. Said movable side wall or press-head 26 is vibrated by a lever 45 fulcrumed on the frame at 29, one end of said lever having a slot 30 engaging a pin 31 on the wall 26 and the other end of said lever having a roller engagement with a cam groove in a cam disk 32 fast on the 50 longitudinally disposed rotary shaft 20 journaled in brackets beneath the table, said latter shaft being continuously driven by the means before stated.

In the present embodiment two presses 55 are employed through which the boxes successively pass, said presses and their operating devices being identical in construction, as illustrated.

Slitter. — After passing through the 60 presses 26, 27, the labeled boxes are operated upon by a cutting device, which slits the labels or covering strips on the boxes on a line opposite the joint on one side of the box, thus leaving the base and cover at the

opposite side of the box hinged by the label. 65 On the shaft 20, at the extreme rear portion of the machine, is a cam disk 33 which causes vertical oscillation of a rock-arm 34 pivoted at one end to a bracket 35 on the table and at its other end joined by a link 36 to a vertically guided reciprocating follower, or box-supporting head, 37, adapted to reciprocate in alinement with a guideway 38. Said guideway is transversely disposed relative to the path of the boxes in the box 75 magazine opposite the position of ejection of the labeled boxes from the lower rotary carrier and comprises front and rear walls 39, the former having an opening 40 to permit the labeled boxes to pass from said press 80 into said guideway at one side of the guideway. The follower 37 has a depending vertically arranged extension or stem in the shape of a plate 41 having oppositely disposed flanges 42, and said depending portion is slotted on opposite sides, as at 43, a series of anti-friction rollers 44 intersecting said slots and being journaled in the flanges 42 by the axles 45, to which said rollers are connected. The plate 41 reciprocates vertically in the transverse guideway and is held in alinement therewith by a suitable bracket on the frame having a plate 45' which bears on the front part thereof, and by a plurality of pairs of bearings or retaining plates 46, 46 fastened to the frame and bracket, respectively, at the rear of the reciprocating plate and against which the anti-friction rollers 44 are adapted to bear. By this construction the follower moves readily up and down under the influence of the rock-arm 90 34, and even though some adhesive should become attached to the follower or its guide, ready movement of the former is permitted on account of the anti-friction rollers. The 95 bearings 46 are out of transverse alinement with the bearing 45', so that there is no tendency for the rollers 44 to drag.

The boxes from the lower turret pass through the presses, which latter, in this 110 instance, become in effect a supply magazine for the guideway 38, and as a labeled box is ejected from the lower carrier, or turret 24, the rearmost of the boxes in the magazine is thrust into the slitter guideway 115 through the opening 40 and takes position upon or opposite the support or follower 37, this latter being in its lower position at that time. A resilient member or plate 47 adjacent the guideway rests upon the tops 120 of the boxes in the magazine, supports them in predetermined position therein, and guides them through the opening 40, the forward end of said plate 47 being curved upwardly and terminating at a point preferably spaced from the path of the boxes when moved in the guideway transversely of said magazine. On the guideway wall 39 oppo-

site the opening 40 is removably and adjustably secured a label-smoothing and pressing device comprising brushes 48 removably attached to a plate 49, said brushes 5 being adapted to contact with the labels on the boxes and smooth and press the same thereagainst as the boxes are lifted by the follower 37. The brushes being spaced apart transversely of the guideway, the overlapping edge of the label will not be disturbed thereby.

Above the opening 40, in the forward plate 39, is a horizontal rotary shaft 50 having removably secured thereto a label-slitting or severing means which, in the present instance, comprises a metallic disk 51 having a sharp generally circular cutting edge, which latter is disposed to project slightly into the guideway through a slot 52 which may be formed in the latter, said disk being disposed in line with the joint 6, at one side of the box as said box is fed by the follower 37. Thus, as the follower is lifted the box is fed past said slitter and the label is severed at one side thereof in line with the joint between the box sections, the other side remaining whole and serving as a hinge for said sections. The walls of the guideway, at opposite sides of the plane of the slitter disk, form abutments with which the box makes contact, and these abutments are a predetermined distance from the operative edge of the disk and within said edge, so that the slitter will not sever the neck of the box.

Directly opposite the edge of said slitter is a pressing roll or roller 53 journaled on the opposite guideway wall and projecting into said guideway in line with the joint of the boxes on the side opposite the severed portion of the label, said roller 53 being adapted to firmly press the label against the box at the joint in order to secure its more efficient attachment at this point and also to press the box toward the slitting disk 51 and against the abutments referred to, the abutments and roll 53 maintaining the roll to be slit in the same plane during the slitting operation. As particles of glue from the boxes might adhere to the walls of the guideway and obstruct free movement of the boxes therethrough, said walls are provided with anti-friction rolls or rollers 54 projecting into the guideway at opposite sides of the plane of the slitter, these rollers having their rotary planes disposed transversely of the plane of the slitter disk. These rollers allow relatively easy movement of the boxes, and at the same time said boxes will be guided in proper position relatively to said slitter and the roller 53 transversely of the rotary plane of the slitter assuring rectilinear movement of the boxes in a plane parallel to the plane of rotation of

the slitter from the beginning to the end of the slitting operation. As illustrated, the upper and lower rolls 54 are spaced apart longitudinally of the path of movement of the boxes a less distance than the length of a box so as to positively guide the boxes while they are being slit. The slitter shaft 50 is supported in bearing boxes fastened to each of two upright yokes 55 and 56, and is provided with a small bevel gear 57 meshing with a larger bevel gear 58 on a shaft 59 continuously driven from the main driving shaft 10 through the instrumentality of a sprocket and chain 60, as illustrated. The slitter revolves very rapidly and makes a very fine cut in the labels, so that the resultant ends thereof are substantially even. The follower 37 not only feeds the boxes past the slitter, but beyond the same into position in rear of a pusher or ejector 61 disposed on the opposite side of the slitter from the box magazine, which pusher reciprocates transversely of the guideway, and as it moves rearwardly, pushes the box off the follower and out of the guideway 38, preferably onto a horizontal platform 62 having lateral walls 63, spring-held or otherwise yielding box-retaining dogs 64 having beveled faces 65 serving to prevent retrograde movement of the boxes into the path of movement of a succeeding box through the guideway. Each dog 64 comprises a plate 66 pivoted at 67 to a wall 63, said walls each having an opening 68 through which the beveled faces of the dog project. A spring 69 serves to maintain the boxes in upright position immediately adjacent the guideway.

The pusher reciprocates horizontally opposite the uppermost position of the boxes and passes between the lateral walls of the guideway. Said pusher comprises a plate which is the termination of a rectangular reciprocatory rod 70, mounted to slide in bearings on the upper portion of the yokes 55 and 56. On the countershaft 17 is a face cam 71 engaged by a roller of a cam rod 72, the adjacent end of which latter is slotted and embraces the shaft 17. The remote end of the rod 72 is bent upwardly and slides in a bracket 73 adjustably fastened at the upper lateral portion of the yoke 56. To the end of the rod 72 is adjustably fixed a laterally disposed connecting piece 74 which latter is also adjustably fastened to the pusher rod 70. Thus, as the shaft 17 rotates, reciprocatory motion is imparted to the pusher rod 70 through the connecting instrumentality just described, so that after each box is slit, it is removed from the slitter guideway by said pusher. The guide walls 39, 39 are preferably cast as a part of substantial frame pieces 75, 75, bolted in position at the rear end of the table 9,

which frame pieces serve as supports for the platform 62 and other adjacent parts hereinbefore described.

The discharger 25 is operated by a reciprocating block 78, radial movement of which is effected by a link 79 pivotally connected at 80 to an oscillatory sleeve 81 on the carrier shaft 82, said sleeve being oscillated by a rod 83 having a roller 84 operating in a cam groove 85 of a cam disk 86 on the counter-shaft 17; all as set forth more particularly in the prior application hereinbefore mentioned.

The operation of the machine may be briefly described as follows: A box, labeled as hereinbefore described, will be placed in position opposite the front end 76 of the magazine 77, and will be moved into the magazine by the discharger 25. The carrier 24 has four pockets 23, and as each arrives opposite the magazine 77 a labeled box is moved into the magazine, until the boxes completely fill the magazine from one end to the other. Thereafter succeeding boxes moved into the magazine will move or feed the rearmost boxes successively into position opposite the head 37, and successive upward movements of the latter will effect relative translatory passing movement between the boxes and the slitter, moving the boxes along the guideway into co-operative relation with the slitter to effect slitting of the part of the box or label in line with the slitter. In the present arrangement the ends of the label do not overlap each other, but are spaced apart on the bottom of the box, and they assume position in the magazine with the end edges of the labels extending upwardly. As the labeled boxes are moved upwardly toward the slitter by the head 37, the brushes 48 smooth and press the ends of the labels against the bottom of the box, and as the boxes are moved past the slitter, the edge of the disk severs the label opposite the joint in the box at one side of the box, the roller 53 pressing the label against the box on the other side opposite the joint, causing the label to securely adhere to the box at the hinge part of the label. In the present case the boxes have just been labeled, and the adhesive or glue is moist and specially adapted for the operations of smoothing and pressing. The box is urged between the rollers 54, and these rollers are disposed to cause the joint of the box held therebetween to align with the edge of the slitter disk 51, so that the label is slit, or severed, directly opposite the joint, the edge of the disk entering between the edges of the flanges of the base and cover. The depth to which the edge of the disk penetrates is not sufficient to mar or slit the neck 4 of the box, as the abutments limit the depth of cut to a distance less than that required to cause contact between the disk and the neck. The

box having passed the slitter, will be in position opposite the ejector 61, and the latter will push the slitted box off the head 37, onto the platform 62, past the dogs 64, which latter will keep the ejected boxes out of the guideway. The plate 41 prevents a succeeding box entering the guideway until the head 37 returns to its initial box elevating position, whereupon the operations are repeated on a succeeding box.

Thus by the above described construction are accomplished, among others, the objects hereinbefore referred to.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent is:

1. In an apparatus of the character described, in combination, a guideway for boxes, a slitter projecting into said guideway, means adapted to move boxes along said guideway into co-operative relation with said slitter, comprising a reciprocating head movable in alinement with said guideway, a slotted flanged plate connected to said head, anti-friction rollers journaled in the flanges of said plate and intersecting said slots, and bearings on opposite sides of said plate with which said rollers contact.

2. In an apparatus of the character described, in combination, a guideway for boxes, a slitter projecting into said guideway, means adapted to move boxes along said guideway into co-operative relation with said slitter, comprising a reciprocating head movable in alinement with said guideway, a stem connected to said head, anti-friction rollers carried by said stem, a stationary frame adapted to serve as a bearing for said rollers at one side of said stem, and a bearing plate at the other side of said stem out of transverse alinement with said frame bearing.

3. In an apparatus of the character described, in combination, a guideway for boxes, a rotary slitter disk projecting into said guideway, a box pressing roller opposite said disk on the opposite side of said guideway, anti-friction rollers projecting into said guideway with their rotary planes

- transversely of the plane of said disk, a laterally disposed box magazine communicating with said guideway, means adapted to feed boxes from the magazine into said guideway, and means adapted to move boxes along said guideway into coöperative relation with said disk.
4. In an apparatus of the character described, in combination, a guideway for boxes, a rotary slitter disk projecting into said guideway, a box pressing roller opposite said disk on the opposite side of said guideway, anti-friction rollers projecting into said guideway with their rotary planes transversely of the plane of said disk, a laterally disposed box magazine communicating with said guideway, a resilient member adapted to contact and support the boxes in predetermined position in the magazine adjacent the guideway, means adapted to feed boxes from the magazine into said guideway, and means adapted to move boxes along said guideway into coöperative relation with said disk.
5. In an apparatus of the character described, in combination, a slitter, a guideway for boxes, means adapted to move boxes along said guideway into and out of coöperative relation with said slitter, means adapted to eject the boxes from the guideway, comprising a reciprocatory pusher adapted to operate transversely of said guideway, a platform onto which the ejected boxes move, and yielding box retaining dogs adapted to prevent retrograde movement of the ejected boxes into said guideway.
6. In an apparatus of the character described, in combination, a guideway for boxes, a rotary slitter disk projecting into said guideway, a laterally disposed box magazine communicating with said guideway at one side of said disk, a box ejector operating transversely of said guideway at the opposite side of said disk, a reciprocatory head movable in alinement with said guideway adapted to move boxes in succession into coöperative relation with said disk and thence opposite said ejector, means adapted to move boxes from said magazine into the path of said head, and means adapted to reciprocate said ejector.
7. In an apparatus of the character described, in combination, a guideway for two part boxes having a label across their joint, a rotatable slitter the edge of which projects into said guideway in line with the joint between the parts of said boxes, means adapted to move said boxes past said slitter in contact therewith, and means adapted to press the labels against the respective boxes at the jointed portion thereof opposite said slitter portion.
8. In an apparatus of the character described, in combination, a guideway for two part boxes having a label across their joint, a rotatable slitter the edge of which projects into said guideway in line with the joint between the parts of said boxes, means adapted to feed said boxes past said slitter in contact therewith, means adapted to press the labels against the respective boxes at the jointed portion thereof opposite said slitter portion, and label pressing means adapted to contact a face of the boxes adjacent said jointed side as said boxes are fed.
9. In an apparatus of the character described, in combination, a magazine for a series of sectional boxes having a label across the joint, means adapted to move said boxes successively from said magazine, a guideway transversely disposed relative to said path of movement of said boxes and into which said boxes are moved, a rotatable slitter the edge of which projects into said guideway, and a reciprocatory follower adapted to move successive boxes along said guideway and thereby cause the label to be severed by the slitter in line with the joint at one side of said boxes.
10. In an apparatus of the character described, in combination, a guideway for two-part boxes having a label across their joint, a rotatable slitter the edge of which projects into the path of the labels of said boxes at the joint, means adapted to feed said boxes in said guideway past said slitter whereby said labels are severed in line with said joint, and means adapted to remove the preceding slitted boxes out of the path of succeeding boxes in the guideway and maintain them out of said path.
11. In an apparatus of the character described, a slitter, means adapted to cause relative translatory passing movement between boxes and the slitter to effect slitting of faces of the boxes and means adapted to maintain predetermined rectilinear movement of the boxes in a plane parallel to the plane of rotation of the slitter from the beginning to the end of the slitting operation, comprising guide rolls disposed to contact the box before and after it is slit, said rolls being spaced apart longitudinally of the path of movement of the boxes a less distance than the length of the box to be slit.
12. In an apparatus of the character described, a slitter, means adapted to cause relative translatory passing movement between boxes and the slitter to effect slitting of faces of the boxes, means adapted to maintain predetermined rectilinear movement of the boxes in a plane parallel to the plane of rotation of the slitter from the beginning to the end of the slitting operation and means adapted to maintain the face to be slit in the same plane during the slitting operation.
13. In an apparatus of the character described, a slitter, means adapted to cause relative translatory passing movement between boxes and the slitter to effect slitting

of faces of the boxes, means adapted to maintain predetermined rectilinear movement of the boxes in a plane parallel to the plane of rotation of the slitter from the beginning to the end of the slitting operation and means adapted to maintain the face to be slit in the same plane during the slitting operation, comprising a roll directly opposite

site the edge of the slitter adapted to press the boxes toward said edge.

In testimony whereof I affix my signature, in the presence of two witnesses.

ROBINSON BURT.
